[57] CLAIM

The ornamental design for a compact screw-in fluorescent lamp, as shown and described.

DESCRIPTION

FIG. 1 is a perspective view of a compact screw-in fluorescent lamp showing my new design;

FIG. 2 is a side elevational view thereof;

FIG. 3 is a side elevational view rotated 90 degrees with respect to FIG. 2;

FIG. 4 is a top plan view thereof;

FIG. 5 is a bottom plan view thereof;

FIG. 6 is a perspective view of a second embodiment of my new design;

FIG. 7 is a side elevational view thereof;

FIG. 8 is a side elevational view thereof rotated 90 degrees with respect to FIG. 7;

FIG. 9 is a top plan view thereof;

FIG. 10 is a bottom plan view thereof;

FIG. 11 is a perspective view of a third embodiment of my new design;

FIG. 12 is a side elevational view thereof;

FIG. 13 is a side elevational view thereof rotated 90 degrees with respect to FIG. 12;

FIG. 14 is a top plan view thereof;

FIG. 15 is a bottom plan view thereof.
